J. S. Piga.
By *John Randolph Jr.* Attorney

UNITED STATES PATENT OFFICE.

JOSEPH S. PIGA, OF OWENDALE, MICHIGAN.

LOCK.

Application filed July 20, 1922. Serial No. 576,320.

To all whom it may concern:

Be it known that I, JOSEPH S. PIGA, a citizen of the United States, residing at Owendale, in the county of Huron and State of Michigan, have invented certain new and useful Improvements in Locks; and I do hereby declare the following to be a full, clear, and exact description of the invention, such as will enable others skilled in the art to which it appertains to make and use the same.

The invention provides a lock of the type embodying a bow or shackle and which is adapted to be opened without requiring the use of a key, the lock bolt releasing means being in the nature of a push button.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a sectional view of parts of a door and door jamb, illustrative of the invention, the lock casing and bow being in section,

Figure 2 is an elevation of a lock embodying the invention,

Figure 3 is a sectional detail on the line 3—3 of Figure 1, and

Figure 4 is a detail view of the lock bolt.

Corresponding and like parts are referred to in the following description and designated in the several views of the drawings by like reference characters.

The numeral 1 designates a door jamb and 2 a door in cooperative relation therewith. A keeper preferably in the form of a large headed screw or stud 3 is applied to the jamb 1 and receives the bow or shackle 4 of the lock when the door 2 is closed and locked. The head of the screw or stud 3 is of such size as to cover and conceal the bow or shackle 4.

The lock comprises a suitable casing 5 having a removable cover plate. The bow or shackle 4 is pivoted to the casing in any preferred way as indicated at 6 and has a projecting arm 7 and lateral extension 8 at the inner end of the arm. A spring 9

normally tends to hold the bow or shackle 4 in open position. As shown, the spring 9 is of the contractile helical type and is connected at one end to the arm 7 and at its opposite end to the casing 5.

A lock bolt 10 is pivoted at 11 to the front and rear walls of the casing 5 and is provided at one end with a catch 12 to engage the lateral extension 8 and hold the bow or shackle 4 in closed or locked position. The opposite end of the lock bolt 10 is provided with a lateral extension 13 which is adapted to project through an opening in the outer or front wall of the casing 5. A spring 14 normally holds the part 13 projected and the catch 12 in engagement with the lateral extension 8. The outer end of the projection 13 is finished to represent the head of a screw and corresponds to the heads of the screws 15 which secure the lock to the door 2. The catch 12 is beveled to ride upon the lateral extension 8 when closing the bow or shackle 4 about the shank of the fastening element 3. When the lock is in position, the projecting end of the part 13 is not discernible from the heads of the screws 15, hence to the uninitiated the lock cannot be opened, but to one familiar with the lock the same may be readily opened by applying pressure to the projecting end of the part 13. The lock bolt 10 is formed with trunnions 16 which have ample play in bearings of the lock casing to admit of free pivotal movement of the lock bolt to engage or release the lateral extension 8 of the bow or shackle as required.

What is claimed is:

1. A lock of the character specified comprising a keeper, a casing, a member pivoted within the casing and having an end portion projecting beyond the casing and constituting a bow and having the other end portion extended within the casing to form an arm and a lateral extension, a spring normally holding the bow in open position, and a lock bolt pivoted within the casing and having a latch at one end to engage the lateral extension of the pivoted member and hold the bow in locked engagement with the keeper, and having the other end appearing opposite an opening in the casing to be pressed upon to release the said pivoted member.

2. A lock of the character specified comprising a keeper, a casing having openings to receive headed fastenings, whereby to

secure the lock to the part to be fastened, a bow adapted to engage the keeper and pivoted to the casing and having a projecting arm and lateral extension, a spring normally holding the bow in open position, and a lock bolt having trunnions by means of which it is pivotally supported within the lock casing, and having a catch to engage said lateral extension of the bow, 10 and having a lateral projection extending

through an opening of the casing and having the projecting part finished to represent the heads of the fastenings.

In testimony whereof I affix my signature in presence of two witnesses.

JOSEPH S. PIGA.
